UNITED STATES PATENT OFFICE.

JOSEPH N. BURNO, OF CHICAGO, ILLINOIS, ASSIGNOR TO BUDDE & WESTERMANN, A CORPORATION OF NEW YORK.

LIQUID-DISPENSING APPARATUS.

Application filed April 19, 1922. Serial No. 555,542.

To all whom it may concern:

Be it known that I, JOSEPH N. BURNO, a citizen of the United States, and a resident of Chicago, county of Cook, State of Illinois, have invented certain new and useful Improvements in Liquid-Dispensing Apparatus, of which the following is a specification.

This invention relates to liquid dispensing apparatus and has particular reference to such apparatus of the coin controlled type.

An important object of the invention is to provide in a device of the class mentioned a means whereby the presence of a coin of a given denomination will affect a positive and reliable operation between several cooperative elements of the mechanism to render the same operative for a sufficient length of time to permit the apparatus as a whole to properly function.

A further object is to so construct the various elements entering into the apparatus embodying my invention that the same may be rendered reliable in operation, easily assembled and inexpensive to manufacture.

Other objects and certain advantages of the invention will become apparent from the following description when taken in connection with the accompanying drawings in which:

Figure 1 is a side elevation of the apparatus showing the several cooperative elements thereof in their respective normal positions.

Figure 2 is a view similar to that of Figure 1 illustrating the several cooperative elements as having been moved slightly out of their respective normal positions.

Figure 3 is a view similar to that of Figure 2 showing the several cooperative elements as having been moved slightly further toward their respective operating limits.

Figure 4 is a view similar to that of Figure 3 illustrating the several cooperative elements as having nearly reached their respective limits over a given cycle of operation.

Figure 5 is a sectional view taken on line 5-5 of Figure 1.

Figure 6 is a top plan view of the device with its several cooperative elements positioned as shown in Figure 1.

In the drawings wherein is shown what I at present consider the preferred form of my invention the numeral 5 indicates a base, to which is secured a pair of standards 6, connected together by means of a transversely disposed bar 7 and provided with diverging arms 8 and 9. Upon the bar 7 there is disposed a plate 10, to which is connected a dispensing nozzle 11 divided as by means of a wall 12, into chambers 13 and 14 with which coffee and milk supply pipes 15 and 16 respectively are adapted to communicate. The chambers 13 and 14 are so formed at their lower ends as to provide seats 17 and 18 upon which the lower or closed end of cup-shaped valves 19 and 20 are adapted to seat. These valves are elongated, as shown, and are provided with ports 21 and 22 which are adapted to communicate the interior of the valves with the space afforded between themselves and the walls of the chambers. I have discovered that by constructing the valves as shown the period of their operation may be maintained uniform regardless of what the "head" of milk and coffee at their respective sources might be. Beneath the closed ends of the valves 19 and 20 there is provided a yoke 23, the upturned ends of which extend through the outlet openings 24 and 25 of the chambers 13 and 14 respectively. To the yoke 23 intermediate its ends there is connected a valve actuating rod 26 which extends upwardly through the divisional wall 12 and is connected to a valve actuating lever 27 pivotally connected, as shown at 28, to a support 29.

At the upper end of the arm 8 there is provided a pair of guide studs 30 between which the outer end of combined coin guide 95 and actuating lever 31 extends. This coin guide is provided, at its outer end, with a head 32 having a coin entrance slot 33 formed therein. The coin guide 31 is guided not only by the studs 30 but also by means of a pin 34 operating within a slot 35 formed in an offset portion 36 thereof. It will be noted that the slot 35, substantially throughout its length, is straight but at one end it is diverted to form a cam face 37 which functions cooperatively with the stud 34 to slightly lift the lower end of the guide 31 when the same is retracted against the influence of a coil spring 38 one end of which is con-

nected to the guide as shown at 39 whereas the other end is suitably connected to a stationary anchor 40. To the guide 31, relatively near its lower end, there is connected 5 an upwardly extending arm 41 to which is pivotally connected, as by means of a pin 42, a pawl 43 which is free to swing in one direction but prevented from moving to a vertical position when swinging in the opposite direction by means of a pin 44 carried 10 by the arm 41. The reason for the normally inclined position of the pawl 43 will be appreciated when considering the fact that the same is adapted to function 15 as a cam under certain conditions as will hereinafter more readily appear.

To the arm 9 there is pivotally connected a bell crank lever 45 the upper end of which is provided with a hook 46 the outer end of 20 which is curved as shown, in order that the same may, under certain conditions, be easily lifted over the pin 44 which it is adapted to engage to prevent operation of the apparatus in the absence of a coin. It 25 will be noted that the arm 45 is so shaped that when the coin, as shown at 47, is inserted the same will lie intermediate the offset portion 48 of the arm and the lower end of the guide 31. It is obvious that by 30 moving the guide 31 outwardly against the influence of the spring 38, the lower end thereof will be lifted due to the coaction of the pin 34 with the cam face 37 thereby swinging the arm 45 about its pivot from 35 the position shown in Figure 1 to that of Figure 2. As the arm 45 is lifted the guide 31 is so moved as to release the coin 47 whereupon the arm 45 is allowed to drop to the position shown in Figure 3, it being 40 checked in its movement by a stud 49 adapted to contact with the upper end of the arm 9. Not only does the movement of the guide 31 against the influence of the spring 38 permit the coin 47 to be released, but it at 45 the same time moves the arm 41 a sufficient distance to clear the hook 46 as the arm 45 descends from the position shown in Figures 1 and 2 to that of Figure 3.

To the arm 9 there is suitably connected 50 a pair of brackets 50 which at their free ends are provided with a shaft 51 upon which is mounted a bell crank lever 52 the lower arm of which is provided with a stud 53 adapted to ride up the inclined surface 55 of the pawl 43 when the guide 31 is moved outwardly against the ends of the spring 38. As the stud 53 rides up the inclined pawl 43 the bell crank lever 52 moves about the shaft 51 as a pivot thereby lifting a weight 54 which is carried by an arm 55 suitably connected to the bell crank lever 52 at the upper end thereof. As the bell crank lever 52 is thus moved a pin 56 carried at the lower end thereof is permitted to move 60 under a pivoted cam 57 carried by the ac-

tuating lever 27. After the guide 31 has been moved a sufficient distance to cause the stud 53 to ride over the upper end of the pawl 43 and the arm 41, the bell crank lever 52 is returned to its normal position by the 70 weight 54. During its return movement the stud 56 carried thereby travels up the inclined pivoted cam 57 and thereby depresses the arm 27. When the arm 27 is depressed a weight 58 somewhat lighter than the weight 54 is lifted due to the fact that this latter named weight is carried by an arm 59 which is connected to the end of the arm 27 by means of a link 60. It might be well to remark that it is due to the overbalanced condition of the bell crank lever 52 with respect to the operating lever 27 that the smaller weight is permitted to rise when the bell arm 59 is moved under the influence of the larger weight 54. As the 75 operating arm 27 is moved through the instrumentality of the bell crank lever 52, a piston 61 which is operatively connected with the arm 27 by means of a link 62, is moved downwardly within its cylinder 63 drawing in air through a port 64. This piston serves as a cushioning means for the mechanism when the stud 56 upon return movement is relieved from engagement with the upper face of the pivoted cam 57, 80 the arm 27 being moved upon such disengagement by the influence of the smaller weight 58. It may be remarked here that the arm 27 is free to move upwardly under the influence of the smaller weight 58 upon 85 disengagement of the stud 56 from the cam 57 by reason of the fact that the stud upon completion of its return movement assumes a position at the rear of the cam out of the path of travel of the same. The valves 19 and 20 are lifted when the operating arm 27 is moved downwardly by the action of the bell crank lever 52 and are retained 90 lifted from their respective seats 17 and 18 an appreciable length of time to permit a 95 predetermined amount of liquid to be dispensed. The length of time may be varied to meet the various conditions by adjusting the weight 58 upon its arm 59 to either increase or decrease its leverage, or the opening of the port 64 may be varied as by means of a screw or the like 65 having a tapered flattened side as shown. By moving the weight 58 closer to the pivot connection of the arm 59 the length of time which the valves 100 are maintained open may be increased, or by so adjusting the screw 65 as to retard the escape of air from the cylinder 63 the piston 61 may be retarded in its upward movement thus causing the valves 105 19 and 20 to remain open for a longer length of time. Inasmuch as it is desirable to guide the operating arm 27 in its vertical movement I have provided a pin 66 which projects an appreciable distance from the end 110 115 120 125 130

of the arm 27 and is adapted to operate between a pair of vertically disposed guides 67 which maintain the arm 27 in a vertical plane of operation.

5 Having thus described my invention, I claim:

1. A coin controlled liquid dispensing apparatus having a conduit adapted to carry a liquid, a valve controlling the flow of the liquid through said conduit, a movable coin controlled operating member, means for normally locking said operating member in an inoperative position, means operable in the presence of a coin to release said operating member upon movement thereof, means operable upon a predetermined movement of said member to open said valve, means operable upon the opening of said valve to move the same to its closed position, means for retarding said valve in its movement to closed position, and means for varying the period of operation of said valve closing means.

2. A coin controlled liquid dispensing apparatus having a conduit adapted to carry liquid, a valve controlling the flow of the liquid through said conduit, a movable coin controlled operating member, means for normally locking said operating member in an inoperative position, means operable upon a predetermined movement of said member to open said valve, an operating arm adapted to function upon the opening of said valve to move the same to closed position, and a weight carried by said arm to facilitate its operation, said weight being adapted to vary the period of operation of said valve closing means.

3. A coin controlled liquid dispensing apparatus having a conduit adapted to carry a liquid, a valve controlling the flow of liquid through said conduit, a valve operating arm, a movable coin controlled operating member, means for normally locking said operating member in an inoperative position, said means being operative in the presence of a coin to release said operating member upon movement thereof, valve actuating means adapted to be engaged and moved by said operating member, said means being releasable from said operating member after a predetermined movement thereof, to depress said valve actuating arm.

4. A coin controlled liquid dispensing apparatus having a conduit adapted to carry a liquid, a valve controlling the flow of liquid through said conduit, a valve operating arm, a movable coin controlled operating member, means for normally locking said operating member in an inoperative position, said means being operative in the presence of a coin to release said operating member upon movement thereof, valve actuat-

ing means adapted to be engaged and moved by said operating member, said means being releasable from said operating member after a predetermined movement thereof, to depress said valve operating arm, and means for returning said valve operating arm to a normal position.

5. A coin controlled liquid dispensing apparatus having a conduit adapted to carry a liquid, a valve controlling the flow of liquid through said conduit, a valve operating arm, a movable coin controlled operating member, means for normally locking said operating member in an inoperative position, said means being operative in the presence of a coin to release said operating member upon movement thereof, valve actuating means adapted to be engaged and moved by said operating member and releasable after a predetermined movement thereof, said valve actuating means being adapted to depress said valve operating arm upon means for returning said valve operating arm to normal position, and means for retarding the movement of said operating arm to its normal position.

6. A coin controlled liquid dispensing apparatus having a conduit adapted to carry a liquid, a valve controlling the flow of liquid through said conduit, a valve operating arm, a movable coin controlled operating member, means for normally locking said operating member in an inoperative position, said means being operative in the presence of a coin to release said operating member upon movement thereof, valve actuating means adapted to be engaged and moved by said operating member and releasable after a predetermined movement thereof, said valve actuating means being adapted to depress said valve operating arm upon being released, means for moving said arm to its normal position, means for retarding the movement of said actuating arm to its normal position, the last named means including a dash pot having a piston operatively connected with said valve actuating arm.

7. A coin controlled liquid dispensing apparatus having a conduit adapted to carry a liquid, a valve controlling the flow of liquid through said conduit, a valve operating arm, a movable coin controlled operating member, means for normally locking said operating member in an inoperative position, said means being operative in the presence of a coin to release said operating member upon movement thereof, valve actuating means adapted to be engaged and moved by said operating member and releasable after a predetermined movement thereof, said valve actuating means being adapted to depress said valve operating arm upon being released, means for returning said arm to its normal position, means for retarding the movement of said operating arm to its nor-

mal position, the last named means including a dash pot having a piston operatively connected with said valve operating arm, and means associated with said dash pot for varying the period of operation of said valve operating arm.

8. A coin controlled liquid dispensing apparatus having a conduit adapted to carry a liquid, a valve controlling the flow of liquid through said conduit, a valve actuating arm for opening said valve, a weighted lever connected to said arm for retaining the same in a normal position, a pivoted cam carried by said arm, a movable coin controlled operating member, means for normally locking said operating member in an inoperative position, said means being operable in the presence of a coin to release said operating member upon movement thereof, a lever adapted to be engaged and moved by said operating member and releasable upon a predetermined movement thereof, means for returning said lever to a normal position upon release thereof whereby the same is permitted to coact with said cam to depress said arm thereby opening said valve.

9. A coin controlled liquid dispensing apparatus having a conduit adapted to carry a liquid, a valve controlling the flow of liquid through said conduit, a valve actuating arm for opening said valve, a pivoted cam carried by said arm, a movable coin controlled operating member, means for normally locking said operating member in an inoperative position, said means being operable in the presence of a coin to release said operating member upon movement thereof, a lever adapted to be engaged and moved by said operating member and releasable upon a predetermined movement thereof, means for returning said lever to a normal position upon release thereof whereby the same is permitted to coact with said cam to depress said arm thereby opening said valve, and means cooperating with said arm to return the same to normal position after the same has been depressed whereby said valve is closed.

10. A coin controlled liquid dispensing apparatus having a conduit adapted to carry a liquid, a valve controlling the flow of liquid through said conduit, a valve actuating arm for opening said valve, a pivoted cam carried by said arm, a movable coin controlled operating member, means for normally locking said operating member in an inoperative position, said means being operable in the presence of a coin to release said operating member upon movement thereof, a lever adapted to be engaged and moved by said operating member and releasable upon a predetermined movement thereof, means for returning said lever to a normal position upon release thereof,

whereby the same is permitted to coact with said cam to depress said arm thereby opening said valve, means cooperating with said arm to return the same to normal position after the same has been depressed whereby said valve is closed, and means for varying the period of operation of said arm when being moved to close said valve.

11. A coin controlled liquid dispensing apparatus having a dispensing head provided with chambers, pipes leading to said chambers adapted to carry dissimilar liquids, cup-shaped valves arranged within said chambers to control the flow of liquid from said pipes, a yoke adapted to engage said valves, a valve actuating arm connected with said yoke, a movable coin controlled operating member, means for normally locking said operating member in an inoperative position, means operable in the presence of a coin to release said operating member upon movement thereof, a pivoted cam carried by said arm, a lever adapted to be engaged by said operating member upon movement thereof in a given direction and disengaged therefrom after a predetermined movement of said member, means for effecting a return of said lever to its normal position upon disengagement from said operating member, said lever being adapted to coact with said cam upon its return movement to depress said arm whereby said valves are opened.

12. A coin controlled liquid dispensing apparatus having a dispensing head provided with chambers, pipes leading to said chambers adapted to carry dissimilar liquids, cup-shaped valves arranged within said chambers to control the flow of liquid from said pipes, a yoke adapted to engage said valves, a valve actuating arm, connected with said yoke, a movable coin controlled operating member, means for normally locking said operating member in an inoperative position, means operable in the presence of a coin to release said operating member upon movement thereof, a pivoted cam carried by said arm, a lever adapted to be engaged by said operating member upon movement thereof in a given direction and disengaged therefrom after a predetermined movement of said member, means for effecting a return of said lever to its normal position upon disengagement from said operating member, said lever being adapted to coact with said cam upon its return movement to depress said arm whereby said valves are opened, and means for returning said arm after depression to its normal position whereby said valves are closed.

13. A coin controlled liquid dispensing apparatus having a dispensing head provided with chambers, pipes leading to said chambers adapted to carry dissimilar liquids, cup-shaped valves arranged within

- 5 said chambers to control the flow of liquid from said pipes, a yoke adapted to engage said valves, a valve actuating arm connected with said yoke, a movable coin controlled 50
 5 operating member, means for normally locking said operating member in an inoperative position, means operable in the presence of a coin to release said operating member upon movement thereof, a pivoted cam carried
 10 by said arm, a lever adapted to be engaged by said operating member upon movement thereof in a given direction and disengaged therefrom after a predetermined movement of said member, means for effecting a return 60
 15 of said lever to its normal position upon disengagement from said operating member, said lever being adapted to coact with said cam upon its return movement to depress said arm whereby said valves are opened,
 20 means for returning said arm after depression to its normal position whereby said valves are permitted to close, and means for retarding the movement of said arm to its 65
 25 normal position whereby said valves are retained open an appreciable length of time.
 14. A coin controlled liquid dispensing apparatus having a dispensing head provided with chambers, pipes leading to said chambers adapted to carry dissimilar liquids, cup-shaped valves arranged within said chambers to control the flow of liquid from said pipes, a yoke adapted to engage 70
 30 said valves, a valve actuating arm connected with said yoke, a movable coin controlled operating member, means for normally locking said operating member in an inoperative position, means operable in the presence 75
 35 of a coin to release said operating member upon movement thereof, a pivoted cam carried by said arm, a lever adapted to be engaged by said operating member upon movement thereof in a given direction and disengaged therefrom after a predetermined movement of said member, means for effecting a return of said lever to its normal position upon disengagement from said operating member, said lever being adapted to coact with said cam upon its return movement to depress said arm whereby said valves are opened, means for returning said arm after depression to its normal position whereby 80
 40 said valves are closed, means for retarding the movement of said arm to its normal position whereby said valves are retained open an appreciable length of time, means for varying the period of operation of said arm in its return movement to normal position, 85
 45 and means for returning said operating member to its normal position independently of said means for returning said lever and said arm to their respective normal positions.
 In testimony whereof, I have affixed my signature to this specification.

JOSEPH N. BURNO.
